COVER WITH DISPLAY SUPPORTING STRUCTURE

Hubert V. Bolding, Clarksville, Ind., assignor to Standard Packaging Corporation, New York, N. Y., a corporation of Virginia

Application September 6, 1956, Serial No. 608,388

1 Claim. (Cl. 229—34)

My invention relates to a tray type single blank box structure or cover capable of erection by automatic machinery from a collapsed state and including a pair of corner support means at each corner which provide an elevated support for a mating bottom section containing articles.

This application is a continuation-in-part of my previously filed application Serial No. 536,154, filed September 23, 1955 and entitled, "Tray Type Collapsible Box Structure."

My invention provides opposed side walls operatively connected by force transmitting means to enable automatic set-up by machinery. Built into this box structure without sacrifice of efficiency and speed of automatic set-up are means for providing an elevated support, which means is made up of corner supports hinged to side wall liner panels. These corner supports are swung into operative position during the set-up operation. Each corner of the box or cover structure has two corner supports which abut each other and uniquely strengthen each other to provide supporting pillars of unexpected strength.

Each pair of corner support means has proven to be an exceptionally rigid structure due to a coaction between the elements thereof, this being accomplished without any joining of the elements thereof.

Various other objects and meritorious features of the invention will be apparent from the following description taken in conjunction with the drawings wherein like numerals refer to like parts throughout the several figures and wherein:

Fig. 1 is a plan view of a blank for a box structure with one end partly cut off;

Fig. 2 is a plan view of a box structure made from the blank of Fig. 1 and in collapsed condition ready for erection; this view is on reduced scale;

Fig. 3 is a perspective view of the box structure of Fig. 2 in erected condition with a broken away portion of a box positioned in the box structure in a product display position;

Fig. 4 is a sectional view taken on line 4—4 and rotated 90 degrees of Fig. 3 with the locking means in position for movement to the final locked condition shown in Fig. 5;

Fig. 5 is a view similar to Fig. 4 showing the locking means in locked condition;

Fig. 6 is a top sectional view taken on line 6—6 in Fig. 5; and

Fig. 7 is a sectional end view taken on line 7—7 of Fig. 3.

Referring now to Figs. 1—7, the box structure of my invention comprises a main panel 14 and four side walls 15, 16, 17 and 18 integrally hinged at their inner edges to their respective edges of the main panel. In collapsed condition ready for shipment the first pair of opposed side walls 16 and 18 is swung over the upper surface of the main panel as shown in Fig. 2. The second pair of opposed side walls need not be moved from the original condition in the blank forming the collapsed

2

box structure which is shipped to the user. These walls 15 and 17 extend outwardly from and substantially coplanar with the main panel 14.

The force transmitting means, broadly identified by numerals 60, 61, 62 and 63, which facilitate the erection of the side walls by a simple manipulation of a single pair of opposed side walls, are integrally hinged to the side edges 19—20 and 21—22 of the first pair of opposed side walls 16 and 18. When the carton is in collapsed condition as in Fig. 2, these force transmitting means extend outwardly over the second pair of opposed side walls 15 and 17. Each force transmitting means has a line hinge (23, 24, 25, 26) directed toward its respective corner of the main panel, thereby forming an inner portion (27, 28, 29, 30) and an outer portion (31, 32, 33, 34). Each outer portion is swung into face-to-face engagement with its respective inner portion and is then sandwiched between the inner portion and a predetermined portion of one of the second pair of opposed side walls 15 and 17 as seen in Fig. 2. This forms the box structure in collapsed condition ready for erection by the user.

Line hinges (23, 24, 25, 26) form 45 degree angles with their adjacent side edges (19, 20, 21, 22) of the first pair of opposed side walls. The outer portions (31—34) of the force transmitting means are secured as by glue areas 35, 36, 37, 38 to their predetermined portions of the second pair of opposed side walls.

The box structure is preferably erected by lifting the second pair of opposed side walls 15 and 17 upwardly to the position shown in Fig. 4, this movement automatically erecting the first pair of walls 16 and 18 through the action of the force transmitting means (60—63) described above.

To maintain the erected condition, locking means 39 and 40 are integrally hinged to the outer edges of the second pair of walls 15 and 17, these locking means preferably taking the form of liner panels having retainer lugs 43, 44, 45 and 46. The front wall 18 has a liner panel 50 secured in face-to-face engagement therewith as by gluing as indicated in Fig. 1, the side edges of this liner panel being notched to provide mating notches 51 and 52 for receiving the retaining lugs 43 and 44, respectively. The rear wall 16 has a liner panel 55 secured in face-to-face engagement therewith as by gluing as indicated in Fig. 1, the side edges of this liner panel being notched to provide mating notches 53 and 54 for receiving the retaining lugs 45 and 46, respectively.

As seen in Fig. 4, the liner panel 40 is in condition for downward swinging movement into locked position, this position being shown in Fig. 5 wherein the retaining lug 46 has swung 90 degrees into locking engagement with the notch 54.

As seen in Fig. 3, the box structure of Figs. 1, 2, and 4—7 is specifically designed as a cover which can be inverted to provide elevated support for the article-carrying bottom section of the box and thereby provide an elevated display. This invention is particularly suited for supporting heavy article-containing bottom sections as the design uniquely provides a double support at each corner. These double supports coact and rigidify each other as they are in face-to-face abutting contact.

As seen in Figs. 1 and 2, inner corner support means 90, 90 and 91, 91 are integrally hinged to the side portions of the liner panels 50 and 55, respectively, the line hinges 92 of the corner support means being positioned inwardly of and parallel to the side edges of the liner panels 50 and 55. As will be noted from Figs. 1 and 2, the corner support means 90, 90, 91, 91 extend beyond the side edges of the liner panels.

In assembled condition as shown in Figs. 3—7, the corner support means 90, 90, 91, 91 extend diagonally across

the corners of the main panel 14 and provide supporting surfaces 95 upon which the mating bottom section 96 may rest. As seen in Fig. 3, the mating bottom section 96 has cutouts 97 which hold articles 98 on display. In the structure shown slots 99 are provided in the upper corners of the mating bottom section for receiving the corner supporting means 90, 98, 91, 91 when the cover is placed on the bottom section.

Outer corner support means 93, 93, 94, 94 are integrally hinged to the side portions of locking means 39 and 40, the line hinges 92 of the corner support means being positioned inwardly of and parallel to the side edges of the locking means 39 and 40. It will be noted that the corner support means 93, 93, 94, 94 extend beyond the side edges of the locking means.

As seen in Fig. 4, the corner support means 91 is forced into proper position across the corner of the box when the side walls of the box are brought into vertical position. When the locking means 40 is swung down into the box, the corner support means 94 is brought into face-to-face abutting engagement with the previously positioned corner support means 91 as shown in Figs. 5, 6 and 7. This rigidifies the corner supporting structure at each corner of the box and provides supporting pillars of great strength capable of supporting heavy loads. The hinge lines 92 are scored in a manner such that the corner support means 90, 91, 93, 94 are biased back toward their original position, thereby aiding in the establishment of good abutting contact between each pair of corner support means.

Various other modified forms of the invention will be apparent from the foregoing description and for that reason I wish to limit myself only within the scope of the appended claim.

I claim:

A tray type, single blank, erectable cover comprising when collapsed a rectangular main panel, four side walls integrally hinged at their inner edges to their respective edges of the main panel, a first pair of opposed side walls having liner panels hinged to their outer edges which lie in face-to-face sandwiched engagement between said main panel and said first pair of side walls, a second pair of opposed side walls being coplanar with said main panel,

force transmitting means for facilitating erection integrally hinged to side edges of said first pair of opposed side walls and extending outwardly over said second pair of opposed side walls, each force transmitting means having a line hinge directed toward its respective corner of said main panel which divides each force transmitting means into an inner portion hinged to said side edge and an outer portion, said outer portion being sandwiched between said inner portion and a predetermined portion of the adjacent one of said second pair of opposed side walls, said outer portions being secured to said predetermined portions to facilitate automatic erection, means for maintaining the side walls in erected condition including second liner panels integrally hinged to the outer edges of said second pair of opposed side walls, said liner panels having retaining lugs adjacent their respective hinged connections to the side walls and hinged to the side edges of said liner panels, said first liner panels having mating notches adjacent their respective hinged connections to the side walls for receiving said retaining lugs when said structure is in erected condition, and means for providing an elevated support when the cover is erected and used as a base for its mating bottom section including a corner support integrally hinged to each of the eight side portions of said first and second liner panels at hinge lines inwardly of and parallel to the side edges thereof, the corner supports extending beyond said side edges, adjacent pairs of corner supports which extend from adjacent side portions of said first and second liner panels being in face-to-face abutting relation diagonally across the inside corners of said main panel when in erected condition, each of said corner supports having an outer supporting face spaced a predetermined distance from said main panel to provide for product display.
